CLAIM

The ornamental design for a step light, as shown and described.

DESCRIPTION

FIG. 1 is a front, right-side, top perspective view of a step light;
 FIG. 2 is a back, left-side, bottom perspective view thereof;
 FIG. 3 is a front elevation view thereof;
 FIG. 4 is a back elevation view thereof;
 FIG. 5 is a left-side elevation view thereof;
 FIG. 6 is a right-side elevation view thereof;
 FIG. 7 is a top plan view thereof; and,
 FIG. 8 is a bottom plan view thereof.

The dashed broken lines depict portions of the step light that form no part of the claimed design.
